UNITED STATES PATENT OFFICE.

JOE E. HOWARD AND EMIL M. KNOTHE, OF SEATTLE, WASHINGTON.

AUTOMATIC AIR AND STEAM COUPLING.

1,130,601.

Specification of Letters Patent.

Patented Mar. 2, 1915.

Application filed February 14, 1913. Serial No. 748,371.

To all whom it may concern:

Be it known that we, JOE E. HOWARD and EMIL M. KNOTHE, residing at Seattle, in the county of King and State of Washington, citizens of the United States, have invented a new Automatic Air and Steam Coupler for Any Cars with Air Equipments, of which the following is a specification.

This invention relates to an improved means for connecting the pipes of a train and the principal object of the invention is to provide a device which will so connect the pipes that they will be securely connected, but so connected that they may easily be disconnected when desired.

Another object of the invention is to provide an improved type of coupling means which will permit the pipes to be connected when the cars are on a curve.

Another object of the invention is to so construct the coupler that the pipes will be prevented from being wrenched apart by unevenness in the track-bed.

This invention is illustrated in the accompanying drawings, wherein:

Figure 1 is a side view of a pair of cars with the pipe couplings in a position to be joined. Fig. 2 is a fragmentary end view of one of the cars with certain portions of the pipes shown in section. Fig. 3 is a longitudinal sectional view through the pipe coupler of one car. Fig. 4 is a plan view of one of the couplers with the head shown in section. Fig. 5 is a fragmentary longitudinal sectional view showing the manner of forming tight joints between the ends of the pipes. Fig. 6 is a fragmentary sectional view taken along the line 6—6 in Fig. 4.

In the drawings, the numerals 10 and 11 indicate two cars which are provided with the usual gravity couplers 12 and which are each provided with the improved coupling means for the pipes 13. The coupling means for each car is the same so that a description of one of the coupling means will suffice for both. This coupling means comprises a T-bar 14, which bar is slidably and pivotally mounted in a supporting frame 15 having its arms 16 secured to the bottom of the car. A spring 17 is carried by the frame 15 between the upper and lower bars of the frame and engages the inner end of the T-bar as shown in Fig. 3, so that the T-bar will be normally held in this position with the securing bolt 18 at the rear end of the slot 19 which is formed in the T-bar.

This spring 17 may be soldered to the inner end of the frame 15 or may be secured therein in any suitable manner which is not deemed necessary to be herein shown for retaining the spring in its correct position.

A hollow head 20 is pivotally connected with the neck 21 by means of the pivot pin 22 and is thus permitted to have vertical pivotal movement. The spring 23 is carried by the stem 21' of the neck 21 and engages the head 20, as shown in Fig. 3, so that the head will be yieldably held in the position shown and thus permitted to move vertically to compensate for any jolting due to going over rough places in the road-bed. This neck 21 is pivotally connected with the T-bar by having its stem 21' passed through an opening in the end of the T-bar thus forming a swivel joint. A washer 21² is placed upon the inner end portion of the stem and a cotter pin 21³ is passed through the stem to prevent withdrawal of the stem. The pivotal mounting of the T-bar permits of horizontal side play and it will thus be seen that the heads 20 will at all times be in the proper position.

A pointed finger 24 extends from one side of the head 20 and is intended to fit within the socket 25 of the adjoining head so that the heads 20 of the two cars will be connected and prevented from having any transverse movement. It should be noted, however, that this coupling means for the two heads is of such construction that if the train is broken in the middle, the two heads may easily come apart and thus the train pipes prevented from being wrenched loose.

The train pipes 13 are connected with the short nipples 26 which extend from the head 20 beneath the sliding block 27 mounted in the head. Each of these blocks is provided with a conduit 28 which extends partially through a ring 29 and is yieldably held in this position by the springs 30. When the blocks are in the normal position shown in Fig. 3, the conduit 28 will be out of alignment with the nipples 26 and thus the air in the train pipes will be prevented from escaping. When the cars are coupled, the rings 29 will be brought into engagement as shown in Fig. 5 and the blocks will be moved inwardly against the tension of the springs 30, thus bringing the conduits 28 into alignment with the nipples 26 and permitting the air in the pipes of one car to pass through into the pipes of the second

car. The rings 29 should be made of some material such as rubber so that these rings will form air-tight joints and thus prevent leakage between the rings.

5 The operation of this device may be easily understood from the foregoing description. From this description it will be readily seen that when the couplers of the two cars come together, the points 24 of the pipe couplings 10 will enter the sockets 25 and the rings 29 will abut against each other and move the block 27 inwardly to the position shown in Fig. 5. When in this position, the air will be permitted to pass from the pipes of one 15 car to another. In case the gravity coupler should break and a car become detached from the rest of the train, the points 24 will readily slip out of the sockets 25 and thus disconnect the heads 20, and prevent the 20 train pipes from being wrenched loose. The manner in which the T-bar 14 is mounted permits the train pipes to be connected and disconnected on a curve as well as on a straight length of track, and also permits 25 the cars to turn a curve without any danger of the couplings for the train pipes being wrenched loose. The spring 17 takes up jolts caused when stopping or starting a train, and also assists the springs 30 in keeping 30 the rings 29 of the two couplings in tight engagement.

What is claimed, is:—

1. A train pipe coupler comprising a frame, a spring carried within said frame, 25 said frame provided with laterally extending arms adapted to engage the body of a car for holding the frame in its correct po-

sition, a T-bar slidably mounted within said frame, said T-bar provided with a longitudinal slot, a bolt passing through said slot and engaging the outer portion of said frame thereby limiting the outward movement of said T-bar and also holding said frame together, said T-bar provided with a coupling means at its outer end, said spring 45 being adapted to yieldably hold said T-bar in position.

2. A train pipe coupler comprising a frame, said frame provided with laterally extending arms adapted to engage a car for holding the frame in position, a T-bar slidably mounted within said frame, resilient means carried within said casing for holding said T-bar in an extended position, said T-bar provided with a longitudinal slot, 50 means passing through said slot for limiting the outward movement of said T-bar, a neck rotatably mounted upon the outer portion of said bar and extending into said slot, a washer engaging said neck, means for retaining said washer, whereby said neck may have rotary movement, and a hollow head pivotally secured to said neck, means carried by said head for forming a coupling for train pipes, said resilient means 55 adapted to yieldably hold said T-bar in position, and said neck adapted to allow the coupling to swing or pivot when necessary.

JOE E. HOWARD.
EMIL M. KNOTHE.
